UNITED STATES PATENT OFFICE.

WILSON S. FISTER, OF HAMBURG, PENNSYLVANIA, ASSIGNOR OF ONE-HALF TO SOLOMON E. BEAR, OF HAMBURG, PENNSYLVANIA.

CAR-FENDER.

No. 879,095.

Specification of Letters Patent.

Patented Feb. 11, 1908.

Application filed April 17, 1907. Serial No. 368,674.

To all whom it may concern:

Be it known that I, WILSON S. FISTER, a citizen of United States, residing at Hamburg, in the county of Berks, State of Pennsylvania, have invented certain new and useful Improvements in Car-Fenders; and I do hereby declare the following to be a full, clear, and exact description of the invention, such as will enable others skilled in the art to 10 which it appertains to make and use the same.

This invention relates to new and useful improvements in fenders for tramway cars and it has particular reference to a fender of 15 the pivoted scoop type.

In connection with a fender of the above type, the invention aims as a primary object to provide a novel construction, combination and arrangement of parts, the details of 20 which will appear in the course of the following description, wherein reference is had to the accompanying drawings forming a part of this specification, like characters of reference designating similar parts throughout the several views wherein:—

Figure 1 is a side elevation showing the lower portion of a car with a fender constructed in accordance with the present invention applied thereto. Fig. 2 is a front elevation thereof. Fig. 3 is a central longitudinal section on the line 3—3 of Fig. 2. Fig. 4 is a detailed perspective view of the fender *per se*. Fig. 5 is a detail perspective view of a hanger from which the fender shown in Fig. 4 is suspended, one of such hangers being provided at each side of the car.

Referring specifically to the accompanying drawings, the numeral 1 represents one 40 of the longitudinal car beams, upon which a transverse bar 2 is fixed. Plates 3, preferably cast are fixed to the ends of the bar 2 by screws 4 or other approved fastening means passed through the plates 3 into the bar 2. The wheel guards are designated by 45 the numeral 5 and are curved longitudinally to conform to the curvature of the wheels which they overlie. The guards 5 are also of a substantial semi-circular contour in 50 cross section and at their upper ends are formed with angular straight extensions 6 which are secured by means of screws or other fastening means 7 to the plates 3. The guards 5 adjacent their lower ends are provided with longitudinal slots 8 to receive

therein the extensions 9 of the depending side portions 10 of a fender frame 11, the latter being of rectangular shape and curved in side elevation. The fender 11 is designed to support a suitable mesh in accordance 60 with the common mode of use. Between the ends of the side bars of the frame 11, pintles 12 are provided upon which are loosely mounted the pulleys 13 which are normally held above the rails but which contact therewith when the car swings from 65 side to side under high speed or in rounding curves.

The extensions 9 are apertured to loosely surround transverse pins 14, fixed in the 70 guards 5 and spanning the same. The guards 5 are provided above the slots 8 with vertically extending slots 15 through which leaf springs 16 are passed, the upper ends of said leaf spring being engaged in suitable 75 clips 18 held by bolts 19 threaded through the guards 5. The springs 16 are passed through openings 17 in the upper cross bar of the fender 11, and underlie the side bars of said fender. Said springs are curved in 80 conformity to said side bars and have their lower ends fixed thereto by bolts 20, rearwardly of the pulleys 13. The springs 16 serve to normally maintain the fender 11 above the rails with the pulleys 13 out of contact therewith. The fender is designed in 85 its action to engage an obstacle or obstruction irrespective of its size, and gradually force such obstacle or obstruction to one side of the track out of the path of the car, said 90 fender being of suitable shape to attain this end.

From the foregoing description it will be seen that simple and efficient means are provided for accomplishing the objects of the 95 invention, but, while the elements herein shown and described are well adapted to serve the functions set forth, it is obvious that various minor changes may be made in the proportions, shape and arrangement of 100 the several parts without departing from the spirit and scope of the invention as defined in the appended claims.

What is claimed is:

1. A fender of the type set forth comprising 105 a frame having a longitudinal side portion formed with angular straight extensions, a curved side portion depending from the longitudinal side portion, and a transverse cross bar connecting the longitudinal side portion and the curved side portion, the curved side portion being formed with longitudinal slots, a fender frame having rearward extensions projected 110

through and working in said lower slots, pivot pins fixed in said wheel guards and projected through said extensions, leaf springs projected through said upper slots and having their upper ends fixed to said wheel guards and their lower ends fixed to said fender frame.

5 2. A fender comprising fixed wheel guards, a fender frame pivotally suspended there-

from, and leaf springs having their upper 10 ends fixed to said wheel guards and their lower ends fixed to said fender frame.

In testimony whereof, I affix my signature, in presence of two witnesses.

WILSON S. FISTER.
